UNITED STATES PATENT OFFICE

FREDERICK GEIGER, OF CLEVELAND, OHIO, ASSIGNOR TO THE ENAMEL PRODUCTS COMPANY, OF CLEVELAND, OHIO, A CORPORATION OF OHIO

ENAMELED METAL TOP FOR TABLES AND THE LIKE

Application filed June 16, 1927. Serial No. 199,377.

Enamel ware table tops and the like while satisfactory in general, occasionally show a tendency to warp or buckle as a result of stresses developed in manufacturing. The avoidance of such buckling is essential to satisfactory usage, and the prevention of this difficulty is accordingly highly desirable.

To the accomplishment of the foregoing and related ends, the invention, then, consists of the features hereinafter fully described, and particularly pointed out in the claims, the following description and the annexed drawing setting forth in detail certain structure embodying the invention, such structure being illustrative however of but one of the various ways in which the principle of the invention may be employed.

In said annexed drawing:

Fig. 1 is an inverse plan of a table top embodying the invention; Fig. 2 is a similar view of a larger form of top; Fig. 3 is a section taken on a plane indicated by the line III—III, Fig. 1; and Fig. 4 is a sectional detail taken on a plane indicated by the line IV—IV, Fig. 3.

The reference numeral 1 in the drawing designates a sheet metal top stamped with a flange 2, and enameled or finished in usual or preferred style. Underneath, and within the flange are positioned thrust-strips 3 which ordinarily are of wood, but which in some instances may be of metal in proportionately reduced dimension. These thrust-strips are located at opposed sides, and between such strips an extensor is arranged such as to exert a predetermined thrust between such strips, thereby holding the metal sheet in taut condition sufficient to counteract distortive tendencies. Such extensor may vary somewhat in its detail, but conveniently may comprise a bar 4, generally of wood, but in some instances of metal, depending upon the size and conditions, and engaging between the end of the bar and the adjacent thrust-strip 3 is an extensor screw 5. In a desirable form, this screw may have a head 6 with wrench-facets and bearing directly against a thrust-plate 7 set on the edge of the thrust-strip. The screw 5 is threaded into a support-plate 8 on the end of the bar 4.

It will now be seen that with the thrust-strips 3 located at opposed sides, and the extensor bar and screw 5 positioned therebetween, by turning up the screw, the desired amount of tension may be brought upon the sheet, thus insuring it against distortion. The particular arrangement of the extensor bars will depend in each instance upon the size and relative dimensions of the article, and one or more correspondingly may be employed. In Fig. 1 for a relatively small table top, a single extensor is shown as adequate. With larger articles, two or more such extendors may be arranged, either longitudinally of the article, or more generally transversely.

In this manner, tops for tables, counters or quite extended surfaces generally may be provided, and adequately safeguarded against distortive change, and by virtue of the adjustable screw take up, the tension may be at any time regulated to suit the particular needs. For a cheaper construction, I also contemplate in some instances substituting the adjustable screw by a wedge construction, this to an extent giving some of the advantages of the invention, but less completely than the preferred form as described.

Other modes of applying the principle of the invention may be employed, change being made as regards the details disclosed, provided the means stated in the following claim or the equivalent of such be employed.

I therefore particularly point out and distinctly claim as my invention:

A table top or the like of sheet metal having a marginal flange beneath, thrust-strips within the flange at opposed sides, and permanently retained means for adjustably tensioning the top, said means including an extensor between said strips comprising a bar and an extensor screw bearing between plates at the end of the bar and the edge of the adjacent thrust-strip.

Signed by me this 8th day of June, 1927.

FREDERICK GEIGER.
